Linear Lighting Co., Palisades, N.Y.

Filed Mar. 4, 1968, Ser. No. 10,846

Term of patent 14 years

Int. Cl. D26—02

U.S. Cl. D48—23

FIG. 1 is a perspective view of the top and front of the fluorescent lighting fixture embodying my design, the fixture being broken away to indicate indeterminate length;

FIG. 2 is a left rear perspective view thereof, the fixture being broken away to indicate indeterminate length;

FIG. 3 is a left end elevational view thereof.

The conventional mounting means in FIGS. 2 and 3 are shown in broken lines for illustrative purposes only.

The lighting fixture is broken away in the fixture to indicate indeterminate length.

The bottom of the lighting fixture has substantially similar surface contours to the top.

I claim:

The ornamental design for a fluorescent lighting fixture, as shown and described.
